IONIC TUBE CIRCUITS

Adolf Perelmann, London, England

Application October 22, 1940, Serial No. 362,300
In Great Britain October 23, 1939

10 Claims. (Cl. 175—363)

This invention relates to improvements in ionic tubes.

A tube which can be used in carrying out the present invention consists briefly of an electron emitting cathode, an anode, and situated between the cathode and anode a cylindrical collecting electrode, these three members being arranged within an evacuated envelope, which henceforth will be called a tube. The tube is filled to a low pressure with an inert gas such as helium, argon, neon or mercury vapour and when a potential difference is applied across the cathode-anode, the electrons emitted from the cathode cause ionisation by collision with the atoms of the gas. The electric discharge is then accompanied by a visible glow and, as is well known, the impedance of the tube is very low.

A cold or hot cathode may be used.

It will be appreciated that there is produced by the cathode-anode potential difference an electrostatic field extending from the cathode to the anode longitudinally of the tube and the basic idea underlying the invention is to apply a transverse magnetic field by which the electric current passing from the cathode to the anode may be diverted to the collector electrode.

Thus it is an object of the invention to provide a method of converting direct current into alternating current.

Another object of the invention is to provide a method of converting alternating current of one frequency into an alternating current of another frequency.

Another object of the invention is to provide an electric trigger or relay device which has none of the disadvantages arising from sparking suffered by the known mechanical devices of this type.

Yet another object of the invention is to provide a method of converting direct current into alternating current with the use of a single electric discharge tube instead of, as in the known methods, two such discharge devices.

Other objects and advantages of the invention will become apparent from the following description of the best known methods of carrying out the invention which will be described with reference to the accompanying drawings, in which:

Figure 1 illustrates a method of converting an alternating current of one frequency to an alternating current of another frequency;

Figure 2 illustrates an alternative method of producing the same result;

Figure 3 illustrates a method of converting direct current to alternating current;

Figure 4 illustrates an alternative method of producing the same result;

Figure 5 illustrates yet another method of producing alternating current from direct current;

Figure 6 illustrates a self-excited circuit for converting direct current to alternating current; and

Figure 7 illustrates a method of controlling the strength of a direct current.

Referring now to Figure 1, the tube used comprises an evacuated glass envelope 10 filled with an inert gas to a pressure of the order of one millimetre of mercury. Within it are disposed a cold cathode 11, a cylindrical collecting electrode 12 and a disc anode 13. An alternating potential difference is applied in any known or suitable manner across the cathode-anode. For example, the alternating H. T. may be derived from an induction coil one end of the primary of which is grounded. Externally of the tube is a permanent horseshoe magnet 14 which, when brought near the discharge path between the cathode and anode causes a current to flow through an external load circuit 15 connected with the collector 12.

By varying the position and/or strength of the permanent magnet 14, there can be produced in the load circuit either an intermittent direct current or an alternating current, the frequency of the latter being dependent upon the strength of the transverse magnetic field produced.

A somewhat similar arrangement is illustrated in Figure 2. The tube used is similar to that shown in Figure 1 except that a hot cathode 16 is used. A magnetic field transverse of the electrostatic field is in this case produced by an electro-magnet 17 the strength of which field may be controlled with the aid of a variable resistance 18, the current for the electro-magnet being supplied from battery 19.

An alternating potential difference is applied across the anode-cathode, and by varying the strength of the magnetic field alternating currents of a wide range of frequency can be produced in the external load circuit 15.

By applying a steady direct current or an interrupted direct potential difference across the anode-cathode there is produced in the load circuit an alternating current superimposed upon a direct current.

In Figure 3 there is illustrated an arrangement which is self-exciting for converting direct current into alternating current. Within the tube 20 is arranged a heating filament 21, a cathode 22, a collecting electrode 23 and an anode 24.

Current passing to the anode traverses the coils of an electro-magnet 25, thence to a first primary coil 26 to the positive terminal of a source of direct current, the negative terminal of which is connected with the cathode 22.

When the tube is switched on current passes from the cathode to the anode and the electro-magnet 25 is energised in such manner that the transverse magnetic field produced causes an intermittent current to pass to the collector 23 with which is connected a second primary 27. When the electro-magnet 25 is energised the current to the anode ceases and the current to the collector starts; immediately the anode current ceases the electro-magnet 25 is de-energised and the anode current again starts. Consequently, there is produced in the first primary 26 the positive half-cycles of an alternating current and in the second primary 27 the negative half-cycles of roughly the same alternating frequency. Hence, in the secondary 28 there is produced a full alternating current.

In Figure 4 there is illustrated an arrangement similar to that of Figure 3 except that the two sets of half-cycles produced in the anode and collector circuits respectively are kept separate and by means of the transformers 29 and 30 are used to produce two alternating currents.

In Figure 5 is illustrated an arrangement similar to that of Figure 4 but in which the direct high potential difference applied across the cathode-anode is produced with the aid of a motor generator. In order to assist in the smooth running of the motor generator, and to avoid damage which might otherwise occur at breaks of the anode circuit, the motor generator 31 is shunted by a floating battery 32 in series with a variable resistance 33.

In Figure 6 is illustrated a self-excited parallel type of circuit for converting direct current to alternating current. In this circuit, if small alternating voltages are applied to the collector electrodes 34 and 35 in opposite phases, current from the direct current source is diverted alternately through the two primary windings 36 and 37 respectively of the transformer 38 and, consequently, alternating current is induced into the secondary 39. A small independent source of alternating current could be used to energise the collectors 34 and 35 and to control the frequency of the output but preferably a part of the alternating current output is fed back to energise the collectors and thus to make the arrangement self-exciting. The frequency of operation may be controlled by adjustment of the values of the condenser 40 and the resistance 41, whilst the condenser 42 ensures that the phase of the collector voltage waves is in correct relationship with that of the anodes.

It will be seen that this arrangement operates upon the same principles as those of Figures 3, 4 and 5. When current flows to the anodes 43 and 44 the electro-magnetic coils 45 and 46 are energised and the tube current is diverted to the collectors 34 and 35, thus stopping the anode currents, whereupon the coils 45 and 46 are de-energised and the anode currents start again.

It may be preferable, instead of allowing the charges collecting on the electrodes 34 and 35 to leak away through the condenser 40, to allow these charges to leak away to earth through suitable condensers, in which case the electrodes 34 and 35 should each be connected to earth through a condenser.

In Figure 7 is illustrated methods of controlling the strengths of direct currents.

As shown in Figure 7, the tube comprises an indirectly heated cathode 47, a collector electrode 48 and an anode 49. When a potential difference is applied across the cathode-anode a comparatively large current flows to the anode and a small current to the collector electrode, which latter electrode is connected to earth through a load resistance 50, a load resistance 51 also being inserted in the anode circuit. By increasing the strength of an electro-magnet 52 the anode current may be decreased and the collector current increased. The same effect can, of course, be produced by keeping the strength of the electro-magnet constant and decreasing the potential difference applied across the cathode-anode.

If desired, the current passing through the anode may be passed through the coils of the electro-magnet 52, in which case the system becomes self-exciting and the current generated in the load circuit 50 is of sinusoidal wave form.

It will be appreciated that in all cases control is effected by varying the strength of a magnetic field which is transverse of the electrostatic field; it is not essential that the magnetic field should be exactly perpendicular to the electrostatic field but it should at least be oblique thereto. The strength of the magnetic field can be varied by varying the position of a magnet or the strength of an exciting current of an electro-magnet.

In all of the devices which have been described above for the production of alternating current from a direct current it will be appreciated that if the direct potential difference applied across the anode-cathode changes, for example decreases, the current passing through the electro-magnet also decreases, so that the effect upon the alternating current generated is to decrease its amplitude without substantially affecting its frequency. This is an advantage which is not possessed by the mechanical type of converter.

I claim:

1. A method of modifying an electric current, wherein a potential difference corresponding with the current is applied across the cathode-anode of an ionic discharge tube to produce between the said electrodes an electrostatic field and hence an electric current, modification of the latter current being achieved by applying a magnetic field transversely of the electrostatic field to cause at least a portion of the anode current to be diverted to a collector electrode disposed between the anode and cathode, the desired modified current being produced in an external circuit associated with the said collector electrode.

2. A method as claimed in claim 1, wherein an intermittent direct potential difference is applied across the anode-cathode of the ionic discharge tube in order to produce an alternating current in the collector circuit.

3. A method as claimed in claim 1, wherein an alternating potential difference is applied across the anode-cathode in order to produce an alternating current in the collector circuit, the frequency and amplitude of the alternating current so produced being controlled by varying the strength of the transverse magnetic field.

4. A method as claimed in claim 1, wherein a direct potential difference is applied across the anode-cathode in order to produce an alternating current in the collector circuit, the frequency and amplitude of which alternating current is

controlled by varying the strength of the transverse magnetic field.

5. A method as claimed in claim 1, wherein a direct potential difference is applied across the anode-cathode, and the anode current is passed through the coils of an electro-magnet used to divert the electric discharge to the collector electrode.

6. A method as claimed in claim 1, wherein a direct potential difference is applied across the anode-cathode, and the anode current is passed through the coils of an electro-magnet used to divert the electric discharge to the collector electrode, the system being self-exciting and the interrupted currents produced in the anode and collector circuits respectively being used to induce an alternating current in a circuit associated with said anode and collector circuits.

7. A method as claimed in claim 1, wherein a direct potential difference is applied across the anode-cathode, and the anode current is passed through the coils of an electro-magnet used to divert the electric discharge to the collector electrode, the system being self-exciting and the intermittent currents developed in the anode and collector circuits respectively being used to induce alternating currents in separate circuits associated with the anode and collector circuits respectively.

8. A method as claimed in claim 1 for converting direct current into alternating current, wherein a direct potential difference is applied across the anode-cathode paths of a pair of ionic discharge tubes connected in parallel so as to

produce between each anode and cathode an electrostatic field and hence an electric discharge, intermittent transverse magnetic fields which are 180° out of phase with respect to each other being applied to the tubes in order to produce intermittent anode currents which are used to induce an alternating current in a circuit associated with said anode circuits.

9. A method as claimed in claim 1, for converting direct current into alternating current, wherein a direct potential difference is applied across the anode-cathode paths of a pair of ionic discharge tubes connected in parallel so as to produce between each anode and cathode an electrostatic field and hence an electric discharge, intermittent transverse magnetic fields which are 180° out of phase with respect to each other being applied to the tubes in order to produce intermittent anode currents which are used to induce an alternating current in a circuit associated with said anode circuits, the intermittent transverse magnetic fields applied to the electric discharge within the tubes being produced by electro-magnets energised by currents derived from the anode currents.

10. A method as claimed in claim 1 for controlling the strength of a direct current wherein a direct potential difference is applied across the cathode-anode of the ionic discharge tube and a transverse magnetic field is applied to control the strength of the current generated in the collector circuit.
